UNITED STATES PATENT OFFICE.

CHARLES B. CHATFIELD, OF GRAND RAPIDS, MICHIGAN.

ROAD CONSTRUCTION.

1,269,785.

Specification of Letters Patent. Patented June 18, 1918.

Application filed April 7, 1917. Serial No. 180,405.

To all whom it may concern:

Be it known that I, CHARLES B. CHATFIELD, a citizen of the United States of America, and resident of Grand Rapids, 5 county of Kent, and State of Michigan, have invented certain new and useful Improvements in and Relating to Road Construction, of which the following is a specification.

The invention relates to certain improvements in roadways and in the method of constructing the same; and the objects and nature of the invention will be readily understood by those skilled in the art in the light of the following explanation of the accompanying drawings illustrating what I now believe to be the preferred embodiments of my invention from among other formations, arrangements and constructions within the spirit and scope of the invention.

10 The present invention relates to the construction of concrete, or other long wearing material, roads, and is particularly directed to roads formed with a narrow single track concrete portion, that is, to roads which are 15 formed of a width to accommodate the average four wheeled vehicle. Roads of this narrow width are usually laid through districts where the number of vehicles passing over the roads is small and it is therefore 20 unnecessary to construct a wide road which will accommodate more than a single vehicle, as the number of vehicles met on the road which will require turning out in passing is comparatively small. The expense of 25 construction and maintenance is therefore considerably reduced by constructing these 30 single-track concrete roads.

The fundamental and primary defect and disadvantage in the usual construction of 35 narrow roads of the type referred to and in other constructions in which a material is added to the road proper, has been the formation of ruts or depressions due to the breaking down and separating of the road 40 and the material lying along either side thereof, whereby the abutting edges of the road and the adjacent material separate and assume different levels. When vehicles turn 45 from the road onto the portions on each side it is often exceedingly difficult to regain the road, as the wheels of the vehicle must sur- 50 mount these ruts or depressions so formed, and in turning from and returning to the

road the vehicle is subjected to severe jolts and shocks as the wheels encounter the rough 55 and uneven formation along the edges of the road proper.

It is an object of the present invention to construct a road with adjacent lateral portions, whereby the breaking down and separation between the road and these lateral portions, which results in the formation of ruts and depressions, is overcome and a roadway is formed which presents an even unbroken surface.

It is a further object of the invention to provide means whereby adjacent portions may be added to a hard long wearing material road and be bound thereto at the adjacent edges so that an even unbroken surface 70 is presented by the road and the adjacent portions.

It is a further object of the invention to provide an improved method of constructing roads of the type provided with lateral portions.

It is a further object of the invention to construct a roadway in which the cost of construction and maintenance is low and the disadvantages and defects of prevailing constructions and methods are eliminated.

The invention consists in certain novel features in construction and in combinations and arrangements as more fully and particularly specified hereinafter.

Referring to the accompanying drawings:

Fig. 1, is a vertical transverse section through a portion of a road during the course of construction.

Fig. 2, is a vertical transverse section 90 through a completed roadway constructed in accordance with my invention.

Fig. 3, is a vertical section through a modified form of construction.

In the accompanying drawing I have disclosed a roadway of the type formed of a narrow single track concrete portion provided on each side with parallel adjoining lateral, side or shoulder portions formed of granular material, such as gravel or macadam. I do not wish however, to limit the use of my invention to such a construction as it is clear that it is adapted, as before pointed out, to constructing lateral or shoulder portions to any width, formation, or arrangement of road. For the purposes of

clearness and as an example of the use to which my invention may be put, I have disclosed this type of road construction herein.

In the particular example illustrated, the roadway is formed of a single track concrete portion having adjoining side, shoulder or lateral portions on each side thereof, preferably formed of gravel or macadam, and joined to and connected with the concrete portion along their contacting or abutting edges by a viscous binding medium. The shoulder or lateral gravel portions, thus bound at their edges to the adjacent edges of the narrow concrete portion, are constructed of approximately equal depth or thickness with the concrete portion at their bound edges and gradually lessen in depth outwardly and upwardly to their outer edges, at which point they are preferably of no appreciable depth or thickness.

The central single track concrete portion is formed of a series of base or bed plates of concrete and upon these plates a wearing surface is formed of the desired thickness of a rich mixture. Between these concrete bed plates a space is left to provide the usual expansion joints. The wearing surfaces or top layer of concrete are treated to present a roughened finish to overcome slipping or skidding of vehicles thereon and to assist the wheels thereof in obtaining a hold or grip on the road surface.

In the drawings, I show the sub-base E, formed of cinders, gravel or sand, or a mixture thereof, forming the sub-grade upon which the roadway of my invention is constructed. This sub-base E is laid to form a sub-grade having its maximum depth at its central portion and sloping outwardly and upwardly to the ground level to form bases for the side, shoulder or lateral portions of the roadway. Upon the central portion of the sub-grade I form a series of concrete or equivalent material plates D which are separated by the usual expansion joint. Upon each plate D a layer of concrete (or equivalent material) A is provided to form a wearing surface. The concrete wearing surface or top layer A is preferably formed of a rich concrete mixture, for example, 40% cement, 50% crushed granite or quartzite, and 10% clean sharp sand, and this mixture is formed to make a plastic material which may be readily worked with a trowel or the like instrument.

On both sides of the concrete portions A, D, and upon the upwardly and outwardly extending surfaces of the sub-base E, gravel or macadam is laid with the upper surfaces approximately flush or level with the upper surface of the concrete layer A, at least at the lines of jointure with the concrete layer A. A viscous binding element C connects or binds the abutting edges of the granular sides, shoulders or laterals B and

the narrow concrete road A, D, and prevents the laterals B from separating from the concrete road and forming ruts, depressions, or other objectionable unevenness or roughness between the concrete portion and the gravel laterals.

This binding element C may consist of a mixture of a material consisting of comparatively small articles such as crushed stone, and a viscous substance, as tar, or the like. This mixture provides a mass which is interposed between the adjacent edges of the single track concrete body and the shoulder or lateral portions and permeates or extends and works a distance into the granular masses forming the lateral portions adjacent the road proper, thus binding the lateral portions to the road and forming a construction which prevents the lateral portions from separating or breaking down with respect to the road. In place of a binding element composed of the mixture above referred to, a viscous substance alone may be used. When using a viscous substance, such as tar or the like, as the binding element, the same will be interposed between the adjacent edges of the road proper and the laterals and will permeate and fill the interstices between the particles forming the laterals and thus create a mass or formation at the edge portion of each lateral adjoining the single track concrete body which will bind the laterals to the same and prevent breaking down or separation therefrom.

In constructing a roadway according to the present invention, the concrete portion A, D is first laid on the sub-base E and preferably between opposite parallel forms 1, composed of strips of wood, or other material, which are held in elevated position by stakes or pegs 2. The strips 1 are maintained a distance above the sub-grade E so that there is a space between the sub-grade and the strips and the opposite strips are arranged a distance apart equal to the width of the central or concrete portion of the road to be produced. The concrete bed or base plates D are formed between strips 1 and the concrete when being laid is tamped or forced so that portions thereof will flow outwardly beneath the forms 1 and extend laterally a distance beyond the same. In this manner the concrete portion is formed, with the extensions or flanges D along its lower edges. After the bed or base plates are laid the top layer of rich concrete mixture A is laid between the forms 1 on the plates D and level with the tops of the forms 1. The upper surface of the layer A is then "broomed" or suitably treated to remove a portion of the material and leave the stone particles in the mixture partly exposed and protruding in order to roughen the wearing surface as at F, and prevent vehicle wheel tires slipping or skidding thereon. This ar-

arrangement and construction of the concrete roadway is my preferred form but it is not essential that the concrete portion be constructed of the two grades or layers of concrete. It may be formed of the material of the base plates throughout or of any other desired material. The top or wearing surface A is provided to present a smoother road surface and one which prevents undue slipping or skidding of vehicle wheel tires thereon.

After the concrete portions A D are set, the forms 1 and stakes 2 are removed. The sub grades on both sides of the concrete are then filled in with the material to form the laterals. These laterals or shoulders are constructed with their upper surfaces approximately flush or level with the surface F of the road proper. After the lateral portions are laid and leveled or graded the desired binding element is introduced between the adjacent edges of the laterals and the road proper. As before explained, the binding element may consist of any substance or mixture of a viscous nature which will enter into the masses of the granular lengths of the roadway and approximately into the opposite edges of the concrete length thereof to protect the edges of the concrete length and at each edge thereof form a mass which is of sufficient body to stand up or resist strains and stresses applied thereto and which prevents, due to its somewhat elastic or resilient nature, any separation or breaking down between the granular portions of the road and the intervening concrete body thereof. The essential characteristic of the invention is the introduction of a binding element between the edge of the concrete or permanent length of the roadway and the adjacent portion of a parallel adjoining granular length of the roadway for the purpose of protecting the edge of the concrete length and joining the granular length thereto against breaking down along the joint. In the particular example illustrated, the extensions or flanges D' formed at the lower edges of the concrete plates, project under the adjacent portions of the gravel or macadam and form seats or supports which tend to more firmly maintain the gravel, binding element, and concrete in position. The formation of these extensions or flanges is not however, essential to my invention but merely adds to the strength of the particular construction, and I do not wish to limit my invention to the use of such construction, as it is evident the road proper may be formed with straight side or edge portions.

In forming the lateral portions the material of which they are constructed, may be lessened or decreased in size or diameter of particles at the portion thereof adjacent the road proper, so that when the binding ele-

ment is introduced a more compact solid construction will result adjacent the edges of the road.

After the concrete and the laterals are in place upon the sub-base and are firmly and tightly settled and packed thereon, a suitable binder such as hot tar, asphaltum, or the like, may be poured upon the laterals adjacent the edges of the concrete to prevent the adjacent upper edges of the joined material from breaking down or separating.

In Fig. 3, of the drawings, a modified form of road construction is shown in which the space left by the removal of the forms 1 is filled with a strip of bituminous concrete G. In this form the edges of the abutting materials are all provided with a suitable binder preventing breaking down and separation thereof. This strip of bituminous concrete could be rolled into this space 85 or introduced in any other suitable manner. Under certain conditions bituminous concrete could be rolled or suitably introduced between the adjacent edges of a road proper and the lateral portion or portions to be 90 joined therewith as a substitute for and in place of the type and character of binding element heretofore referred to, or the bituminous concrete could be used in conjunction with a viscous substance to form the 95 binding element between the road proper and the lateral portion or portions.

In a road constructed in accordance with the foregoing description, the disadvantages of prevailing road construction, of the type referred to, are overcome and a road formed of several parallel portions is constructed in which the several portions are bound together at their adjacent edges and an even, unbroken surface is presented thereby.

The invention consists of a structure and arrangement whereby portions may be added to an existing road or one in which a road is constructed of several widths of material and whereby the possibility of the 110 materials separating and breaking down along their lines of jointure is overcome.

In the claims I employ the term "concrete" in a generic sense to include a substantially hard indestructible permanent roadway width without wishing to limit all features of the invention to a roadway width of Portland cement concrete.

I do not wish to limit my invention to any particular materials, nor to any specific arrangement thereof, as it is clear that various changes, modifications, or variations may be resorted to without departing from the spirit and scope thereof. The fundamental and basic feature of the invention consisting 125 in the introduction of a binding means of any suitable character to join and bind the adjacent portions of the several widths of a roadway, and the specific disclosures hereof are of one adaptation and use to which my 130

invention is applicable and of the specific construction and arrangement of the elements thereof which the same may take.

I do not herein broadly claim the road construction method involving that step which consists in introducing a binder where the macadam and concrete widths join, nor the method of repairing or piercing out old concrete roadways by the formation of shoulders embodying bituminous or viscous binding material and macadam or granular material, as such methods are claimed in my co-pending patent application S. No. 233,447, filed May 9, 1918.

15. What I claim is:—

1. A roadway comprising a concrete width and a parallel granular material width, the adjacent edges of the concrete and granular widths being united by interposed binding material.

20. 2. A roadway comprising a foundation, a concrete width, a parallel loose material side width, and intervening binding material.

3. A road comprising a narrow concrete width provided with side widths formed of a granular fragmentary material adjacent thereto and extending laterally therefrom, said side widths diminishing in thickness from edges adjacent the concrete width to 30 their outer edges, and a binding element introduced between the concrete and side widths.

4. A concrete road provided with extensions along its lower edge portion, fragmentary material forming widening means beside said road, intervening binding material between said concrete road and said extensions.

5. A concrete road formed of a base portion and a wearing surface thereon, fragmentary material extending laterally from said concrete road, and a binding element maintaining the portion of said material adjoining the side edge of the concrete in position with respect to said concrete road.

45. 6. A concrete road, widths on each side thereof and spaced a distance therefrom,

and filling material interposed between said concrete road and said widths forming a compact mass therebetween.

7. A concrete roadway pieced out by a macadam or equivalent shoulder, the longitudinal portion of the shoulder that lies along the edge of the concrete length being cemented thereto.

8. A concrete roadway pieced out by a macadam or equivalent shoulder bound to the longitudinal edge thereof by a suitable cementing binder.

9. The method of constructing roads which consists in forming a cement concrete length with a depressed laterally-extending longitudinal-edge portion, and forming a shoulder of macadam or granular material and a suitable bituminous or viscous binder, joining the edge of said length and covering said portion, substantially as described.

10. A roadway comprising a substantially hard permanent width, a shoulder of granular material, and bituminous concrete material intervening between the permanent width and said granular material, substantially as described.

11. A roadway comprising a concrete width having a depressed edge flange, a granular material shoulder, and bituminous concrete material arranged over said flange and intervening between the concrete width and the granular material.

12. A roadway consisting essentially of a cement concrete length, and a parallel granular road material shoulder serving to widen said length and joining a longitudinal edge thereof, said shoulder being reinforced or strengthened against breaking down from said edge.

13. A roadway consisting essentially of a cement concrete length, and a shoulder serving to widen said length and joining and bound to a longitudinal edge thereof, said shoulder embodying a suitable viscous of bituminous binding medium and road metal or granular material.

CHARLES B. CHATFIELD.
